CENTRIFUGAL DEVICE FOR DEHYDRATING A FINE-GRANULAR MATERIAL

Wolfgang Gertrud Joseph Heckmann, Kolin-Deutz, and Joseph Hubert Becker, Kolin-Mulheim, Germany, assignors to Klockner-Humboldt-Deutz Aktiengesellschaft, Kolin, Germany, a German corporation

Application June 28, 1954, Serial No. 439,822

Claims priority, application Germany June 30, 1953

12 Claims. (Cl. 210—72)

The present invention relates to a centrifugal device, and more particularly to a centrifugal device or centrifuge for dehydrating a fine-granular material having a sieve drum which is imparted vibrations by a crank gearing having a connecting rod being connected with the sieve drum by a loose coupling.

It is an object of the present invention to render the loose coupling between the sieve drum and the connecting rod movable to all sides.

It is another object of the present invention to impart a movability to all sides to the end of the connecting rod opposite to the end connected by the loose coupling with the sieve drum.

It is a further object of the present invention to avoid any end pressures caused by swinging or oscillating movements of the sieve drum in the bearing thereof.

Other objects and advantages of the present invention will become clear from the following detailed description thereof, in connection with the accompanying drawing, showing, by way of example, an embodiment of the present invention. In the drawing:

Fig. 1 is a sectional elevation of a centrifugal device according to the present invention;

Fig. 2 is a sectional elevation on a larger scale of a part of Fig. 1;

Fig. 3 is a sectional elevation on a larger scale of another part of Fig. 1, and

Fig. 4 shows a sectional elevation of the part of Fig. 3 turned through 90°.

Referring now to the drawings, it will be seen that a sieve drum 1 is shaped as a frustum of a hollow inverted circular cone having a substantially vertical axis and which is open at the upper end thereof. At the lower end of the sieve drum 1 a substantially horizontal ring-shaped base member or plate 2 is arranged which is preferably offset so as to form substantially horizontal outer and inner portions 2' and 2'' connected with each other by a substantially vertical portion 2''', the outer portion 2' being arranged at a higher level than the inner portion 2''. A substantially frusto-conical cap 3 is attached to the upper or outer portion 2' of the base member 2 by means of the lower marginal portion 3' of a cap 3 so that the cap 3 protects the bearings and springs more fully to be described hereinafter, against water and dirt.

A stationary member 4 designed as a hollow vertical shaft rigidly connected to the frame 5 of the machine projects with its upper end into the frusto-conical cap 3. A hollow vertical body 8 forming part of the driving means of the sieve drum 1 surrounds part of the stationary member 4 against which it abuts by first and second bearings 6 and 7, respectively, the first bearing 6 being enclosed by the cap 3.

The body 8 has an outer collar 8a forming one piece therewith. Along the outer part of the collar 8a are arranged vibrating bodies or members 10 which abut against the outer portion 2' of the base plate 2. Furthermore vibrating bodies or members 11 are arranged on

2

the inner offset portion 2'' of the base plate 2 and abut against a ring 13 which is secured to the body 8 by means of a screw-threaded portion 8'. The vibrating bodies 10, 11 form resilient means and are designed preferably as helical springs. The vibrating bodies or members 10, 11 are inserted in suitable recesses (not shown) of the base plate 2, the collar 8a, and the ring 13 in order to impart to the bodies or members 10, 11 well-defined positions relative to the parts 2, 8a, and 13. The bodies 10, 11 thus serve for transferring the torque from the body 8 to the base plate 2 and to the sieve drum 1 rigidly connected thereto, as more fully described in the copending applications Serial No. 392,659, filed November 17, 1953, now abandoned, and Serial No. 428,266, filed May 7, 1954, for Centrifugal Device for Dehydrating a Fine-Granular Material.

The lower portion 8'' of the body 8 which is arranged below the collar 8a is designed as a pulley provided with grooves for V-belts indicated by the dash-dotted lines 43 which engage a second pulley 15 attached to the upper portion of a shaft 16 of a driving motor 14 secured to the frame 5 of the machine.

A substantially horizontal crank shaft 18 is supported by bearings 34, 35 arranged in the enlarged portion 4' of the stationary member 4 so as to be removable in axial direction. The crank shaft 18 is coupled by a belt pulley 19 and a belt (not shown) with a driving motor (not shown).

The stationary member or shaft 4 is hollow and serves as a housing for a connecting rod 20 the lower end of which is connected with the bend 18' of the crank shaft 18 in the following manner: The end portion 36 of the connecting rod 20 is designed as an independent structural part which is guided on the eccentric part 18' of the crank shaft 18 by means of a bearing 38 (Figs. 3 and 4). Furthermore, the end portion 36 is connected with the connecting rod 20 by means of the bolt 37 so as to form a joint. The end portion 36 of the connecting rod 20 is provided with two lateral holes 36' in which the bolt 37 fastens. Thus it will be seen that the end portion 36 forms together with the joint bolt 37 a Cardan joint connecting the eccentric part 18' of the crank shaft 18 with the connecting rod 20. In this manner a movability to all sides is ensured and any end pressures caused by the oscillating or swinging movements of the sieve body or drum 1 in the bearing 38 are avoided. The bearing 38 is formed preferably by two roller or ball bearings (not shown).

The upper end portion 20' of the connecting rod 20 is guided in a hub 23 by means of a self-aligning roller bearing 22 having barrel-shaped parts 22' and 22'' (Fig. 2). The inner part 22' of the bearing 22 is held by a disc 24 and a nut 25 on the upper end portion 20' of the connecting rod 20 whereas the outer part 22'' is secured to the hub 23 by means of a cap 26 and screws 27 connecting the cap 26 with the hub 23. The hub 23 forms a structural part of the loose coupling connecting the connecting rod 20 with the sieve drum 1 and transfers the axial vibrations to the latter. The loose coupling between the connecting rod 20 and the sieve drum 1 is movable to all sides. In order to accomplish this the hub 23 is provided with a flange 28 held between two annular rubber springs 21. The rubber springs 21 are arranged in axial direction between rings 29 and 30 and are compressed by screw bolts 31 connecting the rings 29 and 30 with each other. For adjusting the initial stress of the rubber springs 21 the screw bolts 31 are preferably surrounded by tubular distance pieces 39, the length of which is adapted so as to result in a predetermined pretension of the rubber springs 21. The lower ring 29 is attached by means of screws 32 to an annular collar 44 attached to the upper end of the hollow

frusto-conical member or cap 3. Thus the connecting rod 20 is connected with the sieve drum 1 in an articulated manner allowing movements to all sides. At the same time the self-aligning roller bearing 22 takes up any longitudinal forces.

A frusto-conical cap 45 is secured to the ring 30 by means of screws 33. The lower edge of the frusto-conical cap 45 is supported by the angular collar 44 so as to form a seal. The rubber springs 21, the bearing 22, and the entire driving mechanism are advantageously protected in this manner against the leaking of dirt and moisture. On the other hand the springs 21 and the bearing 22 are well accessible and easily assembled.

The operation of this device is as follows:

The material to be dehydrated is filled into the sieve drum 1 and after starting the motor 14 and the motor (not shown) driving the belt (not shown) driving the belt pulley 19 the liquid contained in the material to be dehydrated is carried through the perforated wall of the sieve drum 1 as more fully described in the copending applications Serial No. 392,659, filed November 17, 1953, and No. 428,266, filed May 7, 1954, both for a Centrifugal Device for Dehydrating a Fine-Granular Material. The liquid is caught by the annular container 46 from which it is withdrawn through the conduit 47. The dry material travels over the upper rim portion 48 of the sieve drum 1 and enters the annular space 49 between the wall of the container 50 and an outer casing 51 from which it falls downwards into a collecting bin 52. The outer casing 51 is secured to the outer rim portion of the frame 5 which is stiffened in this range by ribs 53. The casings 51 and 54 are rigidly secured to the frame 5 of the machine.

The frame 5 is supported on the foundation 12 by means of soft springs 9 which consist preferably of rubber. Thus the centrifugal device consists of two mass systems in which the sieve drum forms the first mass and the frame inclusive the driving mechanism or device and the casings 51 and 54 the second or counter-mass as more fully disclosed in the copending patent applications mentioned hereinabove. During operation the sieve drum oscillates or vibrates as first mass in the opposite direction to the counter-mass so that a very favorable balancing of the masses is obtained. The proportion of the first mass to the counter-mass amounts preferably to 1:8 to 1:15 so that the amplitude of the vibrations carried out by the frame and the parts rigidly connected therewith is very small. These small vibrations have a favorable effect on the carrying away of the dehydrated material since the formation of bridges by the material in the annular space 49 is avoided.

Preferably the number of revolutions per minute of the crank shaft 18 is chosen in such manner that the natural frequency of the sieve drum 1, i. e. the frequency of the vertical vibrating movements of the sieve drum 1 supported by the vibrating bodies 10, 11 is in resonance with the frequency of the vibrator formed by the crank shaft 18, the connecting rod 20 and the loose coupling connecting the connecting rod with the sieve drum.

The elasticity of the rubber springs 21 is chosen preferably such that these springs yield great forces. In this manner diminishing of the amplitudes of the sieve drum diminish under the damping influence on the load of the sieve drum is avoided.

A special advantage of the centrifugal device according to the invention is the compact structure thereof which is closed on all sides.

The invention is particularly suitable for a centrifugal device having a sieve drum which has preferably a stroke of a few millimeters, for instance 2-6 millimeters.

It is to be understood that numerous changes may be made in the form, construction, and arrangement of the several parts of the illustrated centrifugal device without departing from the spirit and scope of our invention

or sacrificing any of its attendant advantages, the form herein described being merely for the purpose of illustrating the invention.

What we claim is:

- 5 1. A centrifugal device comprising a sieve drum mounted for rotation about its axis and simultaneous vibration along its axis, means for rotating said sieve drum, and means for vibrating said sieve drum including a crank shaft, a connecting rod, a universal joint connecting said crank shaft to said connecting rod, said connecting rod extending generally in the direction of the axis of said sieve drum, and means yieldable in the direction of said axis including a resilient member securing said connecting rod to said sieve drum, said yieldable means permitting yieldingly limited axial and universal movement of said sieve drum with respect to said connecting rod.
- 10 2. In a centrifugal device as claimed in claim 1, said resilient member forming the sole connection between said connecting rod and said sieve drum.
- 15 3. In a centrifugal device as claimed in claim 1, said yieldable means including a hub rotatably mounted on said connecting rod for rotation around the longitudinal axis of the latter, a flange on said hub, resilient elements arranged on and engaged with opposite sides of said flange, and clamping means engaged with said resilient elements for urging same against said sides of the flange, said clamping means being connected with said sieve drum.
- 20 4. In a centrifugal device as claimed in claim 3, an antifriction bearing interposed between said connecting rod and said hub for rotatably carrying the latter on the former.
- 25 5. In a centrifugal device as claimed in claim 3, said resilient elements being in the shape of a pair of annular rubber springs, one arranged on each side of said flange.
- 30 6. In a centrifugal device as claimed in claim 1, said universal joint including a body having a bore, said crank shaft passing through said bore, and said body being in pivotal connection with said connecting rod, the axis of said pivotal connection being perpendicular to the axis of said bore.
- 35 7. A centrifugal device comprising a sieve drum mounted for rotation about its axis and simultaneous vibration along its axis, actuating means mounted for rotation about its axis, resilient means arranged between and operatively connected with said actuating means and said sieve drum, said resilient means being capable of transmitting a rotation of said actuating means to said sieve drum and being capable of yielding in the direction of the longitudinal axis of said sieve drum, so as to permit vibrating movement of said actuating means and said sieve drum relative to each other, an actuator operatively connected with said actuating means for rotating same and said sieve drum, and means for vibrating said sieve drum including a crank shaft, a connecting rod, a universal joint connecting said crank shaft to said connecting rod, said connecting rod extending generally in the direction of the axis of said sieve drum, and means yieldable in the direction of said axis including a resilient member securing said connecting rod to said sieve drum, said yieldable means permitting yieldingly limited axial and universal movement of said sieve drum with respect to said connecting rod.
- 40 8. In a centrifugal device as claimed in claim 7, said resilient member forming the sole connection between said connecting rod and said sieve drum.
- 45 9. In a centrifugal device as claimed in claim 7, said yieldable means including a hub rotatably mounted on said connecting rod for rotation around the longitudinal axis of the latter, a flange on said hub, resilient elements arranged on and engaged with opposite sides of said flange, and clamping means engaged with said resilient elements for urging same against said sides of the flange,
- 50 10. In a centrifugal device as claimed in claim 7, said yieldable means including a hub rotatably mounted on said connecting rod for rotation around the longitudinal axis of the latter, a flange on said hub, resilient elements arranged on and engaged with opposite sides of said flange, and clamping means engaged with said resilient elements for urging same against said sides of the flange,
- 55 11. In a centrifugal device as claimed in claim 7, said yieldable means including a hub rotatably mounted on said connecting rod for rotation around the longitudinal axis of the latter, a flange on said hub, resilient elements arranged on and engaged with opposite sides of said flange, and clamping means engaged with said resilient elements for urging same against said sides of the flange,
- 60 12. In a centrifugal device as claimed in claim 7, said yieldable means including a hub rotatably mounted on said connecting rod for rotation around the longitudinal axis of the latter, a flange on said hub, resilient elements arranged on and engaged with opposite sides of said flange, and clamping means engaged with said resilient elements for urging same against said sides of the flange,
- 65 13. In a centrifugal device as claimed in claim 7, said yieldable means including a hub rotatably mounted on said connecting rod for rotation around the longitudinal axis of the latter, a flange on said hub, resilient elements arranged on and engaged with opposite sides of said flange, and clamping means engaged with said resilient elements for urging same against said sides of the flange,
- 70 14. In a centrifugal device as claimed in claim 7, said yieldable means including a hub rotatably mounted on said connecting rod for rotation around the longitudinal axis of the latter, a flange on said hub, resilient elements arranged on and engaged with opposite sides of said flange, and clamping means engaged with said resilient elements for urging same against said sides of the flange,
- 75 15. In a centrifugal device as claimed in claim 7, said yieldable means including a hub rotatably mounted on said connecting rod for rotation around the longitudinal axis of the latter, a flange on said hub, resilient elements arranged on and engaged with opposite sides of said flange, and clamping means engaged with said resilient elements for urging same against said sides of the flange,

said clamping means being connected with said sieve drum.

10. In a centrifugal device as claimed in claim 9, an antifriction bearing interposed between said connecting rod and said hub for rotatably carrying the latter on the former.

11. In a centrifugal device as claimed in claim 9, said resilient elements being in the shape of a pair of annular rubber springs, one arranged on each side of said flange.

12. In a centrifugal device as claimed in claim 7, said universal joint including a body having a bore, said 10 crank shaft passing through said bore, and said body being

in pivotal connection with said connecting rod, the axis of said pivotal connection being perpendicular to the axis of said bore.
